(57) **CLAIM**

The ornamental design for a flexible optic, as shown and described.

DESCRIPTION

FIG. 1 is a perspective view of an embodiment of the ornamental design for a flexible optic.

FIG. 2 is a top view of the embodiment of the ornamental design for the flexible optic of FIG. 1.

FIG. 3 is a side view of the embodiment of the ornamental design for the flexible optic of FIG. 1, the front, back, and opposite side views being identical.

FIG. 4 is a bottom view of the embodiment of the ornamental design for the flexible optic of FIG. 1.

FIG. 5 is a perspective view of another embodiment of the ornamental design for a flexible optic.

FIG. 6 is a top view of the embodiment of the ornamental design for the flexible optic of FIG. 5; and,

FIG. 7 is a bottom view of the embodiment of the ornamental design for the flexible optic of FIG. 5.

The broken-line disclosure in the views is understood to represent portions of the article in which the claimed design is embodied, but which form no part of the claimed design.

1 Claim, 7 Drawing Sheets
